UNITED STATES PATENT OFFICE

JOSÉ MIERES, OF BUENOS AIRES, ARGENTINA

GARTER

Application filed July 25, 1931, Serial No. 553,117, and in Germany May 18, 1931.

This invention relates to garters and the like and more particularly to garter fastening means.

The main objects of this invention are to provide an improved form of garter for supporting garments such as socks, stockings and the like, whereby a minimum amount of pressure is required to maintain the garter in position so that the circulation of the blood and the movements of the body are unimpaired; to provide a simple and efficient means for retaining said garter in position on the body; and to provide an improved arrangement of garment fastening means which will permit the garter to be concealed by the garment to be supported.

An illustrative embodiment of this invention is shown in the accompanying drawing, in which:

20 Figure 1 is a perspective view of a complete garter showing one of the garment holding means in a locking engagement with a fragmentally represented portion of a garment.

25 Fig. 2 is a fragmental face view of the garment holding means in open position.

Fig. 3 is a sectional view of the same taken on the line A—B of Fig. 2.

30 Fig. 4 is a fragmental face view of the garter showing by full lines the garment holding means in closed position. The dotted outlines show the parts in locked position.

Fig. 5 is a sectional view of the garter with the garment holding means removed.

35 In the form shown, the improved garter comprises an annular band of elastic material adapted to be slipped upon the limb of the wearer at any desired place. The inner surface of the band is made up of a flat smooth surface pitted with closely spaced non-communicating depressions or vacuum cups 2 which act as suckers when in contact with the skin and retain the garter in position upon the limb. The depressions enable the band 40 to adhere to the skin without causing discomfort to the wearer, since the pressure required to make proper contact with the skin is very slight.

50 Pockets 3 house and secure the plates 4 of the fasteners and are integrally formed

on the band 1 and have outwardly projecting annular bosses or necks 5, provided with openings, as shown in Fig. 5. The plate 4 has a headed stud 6 formed integrally thereon, which may be pressed through the opening in the boss 5, as shown in Fig. 3.

The upper portion of the plate 4 is provided with spaced upstanding lugs 9 forming a pivotal connection for a crank link 10. The middle portion of the crank link 10 is 60 pivotally connected to the upper end of the clasp 7. The upper medial portion of the plate 4 is also provided with a detent or stop 11 in the form of an upwardly and forwardly projecting curled lip or tongue for limiting 65 the backward movement of the clasp 7 when in its garment clasping position.

In assembling the construction, the plate 4 is inserted into the pocket 3 until the head of the stud 6 is opposite the opening in pocket 3. 70 As the pocket 3 is constructed of elastic material, it readily yields to permit the insertion of the plate 4 and stud 6 into the pocket 3 and allows the head of the stud to be forced through the opening in the pocket 3 and neck 75 5, as clearly shown in Fig. 3.

In operation, the band 1 is slipped over the limb and positioned thereon so that it assumes the same position as the top of a garment or stocking subsequently drawn up on 80 the limb. In this position, the top of the garment will conceal the garter and since the head of the stud 6 is covered thereby, it is only necessary to press the clasp 7 over the garment 8 and stud, so that the stud will enter the large portion of the keyhole aperture in the clasp 7, which is then pushed upwardly to clasp the garment. (See Fig. 4.) The crank 10 will be turned upwardly, and backwardly by the upward movement of the clasp 90 7, which is then pushed backward slightly beyond a dead center so that the pull of the garment on the clasp tends to lock it against the detent 11.

To remove the garment, the crank 10 is 95 drawn outward to release the clasp 7 and permit it to be moved down to release the stud from the keyhole aperture, as usual in such devices.

It will be understood that some of the de- 100

tails shown may be altered or omitted without departing from the spirit of the invention, as defined by the following claims:

I claim:

5. 1. A garter comprising a band of elastic material having a pocket formed integrally thereon, said pocket being open at the top and provided with an aperture in its outer wall, in combination with a fastener comprising a 10 substantially flat plate fitting within said pocket, a headed stud formed on said plate and projecting through the aperture in said pocket, a rigid link hingedly connected to the upper end of said plate, and a clasp hingedly connected to said link and having a keyhole 15 aperture to cooperate with said stud for securing a garment thereto.

2. A garter comprising a band of elastic material having a pocket formed integrally 20 thereon, said pocket being open at the top and provided with an aperture in its outer wall, in combination with a fastener comprising a substantially flat plate fitting within said pocket, a headed stud formed on said plate and projecting through the aperture in 25 said pocket, lugs on the upper end of said plate above said pocket, a crank link pivotally connected to said lugs, and a clasp pivotally connected to said crank link and having a 30 keyhole aperture to cooperate with said stud for securing a garment thereto.

3. A garter comprising a band of elastic material having a pocket formed integrally 35 thereon, said pocket being open at the top and provided with an aperture in its outer wall, in combination with a fastener comprising a substantially flat plate and projecting through the aperture in said pocket, a rigid 40 link pivotally connected to the upper end of said plate, a clasp pivotally connected to said link and having a keyhole aperture to cooperate with said stud for securing a garment thereto, and a 45 detent on the upper end of said plate adapted to serve as a lock for holding said clasp in its garment holding position.

4. A garter comprising a band of elastic material having a pocket formed integrally 50 thereon, said pocket being open at the top and provided with an aperture in its outer wall, in combination with a fastener comprising a substantially flat plate fitting within said 55 pocket, a headed stud formed on said plate and projecting through the aperture in said pocket, lugs on the upper end of said plate above said pocket, a crank link pivotally connected to said lugs, a clasp pivotally connected to 60 said link and having a keyhole aperture to cooperate with said stud for securing a garment thereto, a detent on the upper end of said plate adapted to hold said clasp when said clasp is pressed rearwardly toward said band beyond its dead center position.

5. A garter comprising a band of elastic material having a pocket formed integrally 65 thereon, said pocket being open at the top and

provided with an aperture in its outer wall, in combination with a fastener comprising a substantially flat plate fitting within said pocket, a headed stud formed on said plate and projecting through the aperture in said 70 pocket, lugs on the upper end of said plate above said pocket, a crank link pivotally connected to said lugs, a clasp pivotally connected to said crank link and having a keyhole aperture to cooperate with said stud for securing a garment thereto, a detent on the upper end of said plate in the form of an upwardly and forwardly projecting tongue adapted to hold said clasp when said clasp is 75 pressed rearwardly toward said band beyond its dead center position.

6. A garment comprising a band of elastic material having an elastic pocket formed integrally thereon, said pocket being open at the top and provided with an aperture in its outer wall and a projecting neck surrounding said aperture, in combination with a fastener comprising a substantially flat plate fitting within said pocket, a headed stud formed on said plate and projecting through the aperture in said pocket and said neck, a rigid link hingedly connected to the upper end of said plate, and a clasp hingedly connected to said link and having a keyhole aperture to cooperate with said stud for securing a garment thereto.
